(57) CLAIM

The ornamental design for a jewelry vending machine, as shown and described.

DESCRIPTION

FIG. 1 is a top perspective view of a jewelry vending machine, showing my new design;

FIG. 2 is a front view thereof;

FIG. 3 is a rear view thereof;

FIG. 4 is a left side view thereof, the right side view being a mirror image thereof;

FIG. 5 is a top view thereof; and,

FIG. 6 is a bottom view thereof.

The broken lines shown in the figures form no part of the claimed design.
